UNITED STATES PATENT OFFICE.

ANDREW J. SANFORD, OF NEWARK, OHIO, ASSIGNOR TO A. H. HEISEY & COMPANY, OF NEWARK, OHIO.

DESIGN FOR A VASE.

47,739.

Specification for Design.

Patented Aug. 17, 1915.

Application filed June 3, 1915. Serial No. 31,995. Term of patent 14 years.

To all whom it may concern:

Be it known that I, ANDREW J. SANFORD, a citizen of the United States, and residing at Newark, in the county of Licking, State of Ohio, have invented a new, original, and ornamental Design for a Vase, of which the following is a specification, reference being had to the accompanying drawing, forming part thereof.

The figure is a perspective view of a vase, showing my new design.

I claim:

The ornamental design for a vase, as shown.

ANDREW J. SANFORD.

Witnesses:

H. C. MUELLER,
HESTER WOLFORD.
